UNITED STATES PATENT OFFICE.

ORVILLE C. KIRKPATRICK, OF DALLAS CITY, ILLINOIS.

BAG-HOLDER.

1,037,265.

Specification of Letters Patent. Patented Sept. 3, 1912.

Application filed February 26, 1912. Serial No. 679,891.

To all whom it may concern:

Be it known that I, ORVILLE C. KIRKPATRICK, a citizen of the United States, residing at Dallas City, in the county of Hancock and State of Illinois, have invented certain new and useful Improvements in Bag-Holders; and I do declare the following to be a full, clear, and exact description of the invention, such as will enable others skilled 10 in the art to which it appertains to make and use the same.

This invention relates to improvements in bag holding and supporting devices.

One object of the invention is to provide a 15 bag holder and supporting devices having an improved means for detachably securing a bag thereto whereby the bag may be supported and held in position to receive the material placed therein.

Another object is to provide a bag holder 20 which may be applied to a vessel or utensil for supporting the bag therein and which is provided with separable folding supporting members, and a folding handle adapted to 25 be detachably and interchangeably secured to the holder.

Another and important object of the invention is in the provision of a device of the 30 character referred to which can be suspended from a support or readily removed therefrom and placed upon the floor as may be found most convenient without detracting from the utility and advantages of the invention.

With these and other objects in view, the 35 invention consists of certain novel features of construction, and the combination and arrangement of parts as will be more fully described and claimed.

In the accompanying drawings, Figure 1 40 is a perspective view of my improved bag holder and its supporting mechanism showing a bag applied to and supported thereby; Fig. 2 is a central vertical sectional view of the bag receiving member; Fig. 3 is a fragmentary sectional perspective view of the base ring of the supporting mechanism; Fig. 4 is a perspective view of the bag fastening ring; Fig. 5 is a perspective view of 45 one of the sections of the base or supporting ring shown in Fig. 1; Fig. 6 is a side view of the holder showing the detachable handles applied thereto and the holder and bag supported thereby, the ring in the handle being engaged with a suitable support; Fig. 7 is a 50 perspective view of the handles removed

from the holder; Fig. 8 is a similar view of the handle with the parts in folded position; Fig. 9 is a vertical sectional view through a coffee pot showing the holder arranged 60 therein for supporting a coffee holding or percolating bag; Fig. 10 is a perspective view of a funnel which is preferably employed in connection with the holder for facilitating the filling of the bag.

My improved bag holder and supporting device comprises a circular bag receiving member comprising a metal ring or band which flares outwardly from its lower toward its upper edge and has on its upper edge an outward radially projecting flange 2 and on its inner edge an inwardly extending annular bag supporting flange 3, the inner edge of which is turned upwardly to form a rib or bead 4. In the flange 2 and spaced equal distance apart are apertures 5 the purpose of which will be hereinafter described. Adapted to be engaged with the flange 3 is a bag fastening ring 6 which is adapted to fasten the upper end of the bag 70 to the holder. In applying the bag to the holder the bag is first turned inside out after which the fastening ring 6 is inserted into the open end of the bag and said open end and ring are then applied to the holder 75 and the ring engaged with the flange 3 whereupon the bag is pushed down through the holder thus again turning the bag right side out. After the bag has thus been pushed through the holder and turned right 80 side out the open upper end of the bag will be folded around the ring 6 which will securely hold said folded upper end of the bag 85 in engagement with the flange 3 and rib or bead 4 as clearly shown in Fig. 2 of the 90 drawings. When the bag has thus been secured in the holder the same may be engaged with any suitable support or may be applied to or arranged in the upper end of a coffee pot or other form of cooking utensil or vessel whereby the bag will be supported to hang down in the utensil or vessel as clearly shown in Fig. 9 of the drawings.

In connection with the holder, I preferably employ a supporting mechanism comprising a plurality of supporting rods or bars 8 which may be of any suitable length and which are reduced and threaded at their upper ends, said reduced ends forming stop shoulders 9 with which are engaged stop nuts or washers. The reduced threaded upper ends of the rods are adapted to be en-

gaged with or inserted through the apertures 5 in the flange 2 of the holder and said ends of the rods are secured in engagement with the stop flange by clamping nuts 10 5 screwed onto the threaded upper ends of the rods as shown. The lower ends of the rods are bent at right angles and said angularly bent ends are threaded to receive clamping nuts 11. When thus arranged the lower 10 ends of the rods are adapted to be secured to a base or supporting ring 12 having therein rod fastening holes 13 and 14 which are arranged in pairs and spaced equal distances around the ring 12 as shown. In attaching 15 the lower ends of the rods to the ring, said ends are preferably engaged with the inner side of the ring and the angularly bent threaded ends are inserted through the holes 13 in the ring and the nuts 11 screwed 20 on said ends. The lower portions of the rods are further secured to the ring 12 by clamping hooks 15 which are engaged with the rods and have one end projecting through the holes 14, said ends of the hooks 25 being threaded and having screwed thereon, clamping nuts 16 whereby the hooks are fastened in position to clamp the ends of the rod to the ring.

The ring 12 is preferably formed of a 30 series of segmental sections, the ends of which are bent to form interlocking connections whereby said sections may be detachably secured together to form the ring and may be readily disconnected to permit 35 the ring to be taken to pieces and folded in compact form. When the ring 12 is formed in detachable sections, the holes 13 and 14 are preferably arranged through the joined ends of the sections as herein shown, and 40 the ends of the rods 8 and the clamping hooks 15 which engage the holes serve to firmly fasten the joined ends of the sections together.

In addition to the supporting mechanism 45 herein described, I also preferably provide a handle or supporting mechanism by which the holder and bag may be attached to and suspended from a hook, rod or other suitable support *a* as clearly shown in Fig. 6 of the drawings, the handle and suspending or supporting mechanism also serving as a carrying mechanism whereby the holder and the bag attached thereto may be conveniently lifted and carried from place to place. 50 The handle or carrying mechanism comprises a ring 17 having a depending stem or shank 18 the lower end of which is offset or headed as shown. Pivotaly connected to the shank 18 are a series of holder attaching 55 rods 19, which are preferably of right angular form and have their ends reduced and threaded. The reduced threaded ends of the rods form stop shoulders with which are engaged stop washers or nuts 20. When the 60 handle is to be applied to the holder, the 65

upper ends of the supporting rods 10 are disconnected from the holes 5 in the flange 2 of the holder and with said holes are engaged the threaded ends of the rods 19. When thus engaged the washers or nuts 20 70 on the threaded ends of the rods engage the upper side of the flange 2 and on the threaded ends of the rods below the flange are screwed clamping nuts 21 whereby said ends of the rods are securely fastened to the 75 holder. The upper ends of the rods are preferably bent into the form of eyes 22 which are engaged with the stem of the ring 17 whereby the rods are pivotally secured to said stem, so that when the handle is not 80 in use and disconnected from the holder, the rods may be folded together in compact form as shown in Fig. 8 of the drawings. By thus constructing and arranging the holder and its supporting mechanism it will be seen 85 that a bag may be supported at a suitable elevation and held open to receive the material to be placed therein and in order to facilitate the filling of the bag when thus supported and to prevent the material from 90 dropping onto the folded upper edge of the bag, I preferably employ a funnel 23 which is inserted in the holder and engages the upper portion of the bag.

While the invention is particularly designed for holding and supporting a bag for straining jelly, fruits, milk or the like, or for extracting honey or for filtering purposes, it is obvious that the device may be constructed of sufficient size and strength 100 for holding and supporting bags or sacks to be filled with grain or other products of food stuffs.

From the foregoing description taken in connection with the accompanying drawings, the construction and operation of the invention will be readily understood without requiring a more extended explanation.

Various changes in the form, proportion and the minor details of construction may 110 be resorted to without departing from the principle or sacrificing any of the advantages of the invention as claimed.

Having thus described my invention, what I claim is:—

1. A bag holding and supporting device comprising a band, means to secure the mouth of a bag to said band, a plurality of supporting rods the upper ends of which are detachably secured to the band, and a base 120 ring detachably secured to the lower ends of said rods, said ring being composed of a plurality of curved sections the ends of which are provided with hooks for interlocking engagement, the lower ends of said rods being detachably connected to the band at the connected ends of the sections.

2. In a bag holder, a support, a holding band having on its upper edge an upwardly projecting radial flange, a plurality of sup- 130

- porting rods having reduced threaded upper ends adapted to be inserted in the apertures in the flange of said band, said threaded ends of the rods having shoulders thereon forming stops which engage the under side of said flange, clamping nuts adapted to be screwed onto the upper ends of the rods, said rods also having right angularly disposed lower portions having threaded ends, 5
- 10 a base ring formed of a plurality of detachably connected sections having therein pairs of apertures, one of each pair being adapted to receive the threaded angularly bent lower side of a rod, clamping hooks engaged with the rods and inserted in the other apertures 15 in the base ring, and clamping nuts adapted to be screwed onto the ends of the hooks, and on the projecting threaded ends of the rods, whereby said parts are detachably secured to the sections of the base ring. 20

In testimony whereof I have hereunto set my hand in presence of two subscribing witnesses.

ORVILLE C. KIRKPATRICK.
